BAGS

Adolph Potdevin, Westwood, and Rudolph P. Bechle, Wyckoff, N. J., assignors to Potdevin Machine Co., Teterboro, N. J., a corporation of New York

Application December 7, 1955, Serial No. 551,550

4 Claims. (Cl. 229—53)

This invention relates to paper bags, with particular reference to gusseted, long-lip, square bags.

One of the objects of the invention is to provide a gusseted bag of the type just referred to in which the bottom of the bag is superior to that in bags of this general type as heretofore constructed in that provision is made to hold the ends of the gussets securely in place, thereby preventing displacement of the gussets and bag leakage.

The improved bag has a full side seam, so that both walls of the bag are available for printed matter or decorative purposes, and is fabricated from a single blank, the two ends of which are so shaped as to be complementary to each other, thereby eliminating waste of material.

In the accompanying drawings, wherein two embodiments of the invention have been illustrated,

Fig. 1 is a plan view of the bag blank before folding;

Fig. 2 is a front elevation, with one corner in section, of a bag fabricated from the blank of Fig. 1;

Fig. 3 is a plan view of another bag blank, before folding, incorporating a second embodiment of the invention; and

Fig. 4 is a view similar to Fig. 2 showing a bag fabricated from the bag blank of Fig. 3.

Referring, first of all, to the embodiment of the invention as illustrated in Figs. 1 and 2:

The bag is fabricated from the single blank illustrated in Fig. 1, this blank providing a panel or wall 2, seam area 4, panel or wall 6, and gusset areas 8 and 10, the gusset area 8 being intermediate panel 2 and seam area 4, and gusset area 10 being intermediate panels 2 and 6.

As will be seen from Fig. 1, the blank is shaped to provide a lip 12 at one side edge of the panel or wall 2, the lip projecting beyond the upper edge 14 of the panel and embracing or overlapping the upper end of the seam area 4 as well as the upper end of gusset area 8. At the other side edge of the panel or wall 2 is a projecting lip 16, which, like the lip 12, projects beyond the upper edge 14 of the front panel or wall 2. The lip 16 embraces or overlaps the upper end of the panel or wall 6 and the upper end of gusset area 10.

The two outer edges 18 and 20 of the two lips 12 and 16, respectively, are continuations of the straight edges 22 and 24 of the blank. The outer end 26 of the lip 12, however, beginning at a point just above the upper edge of panel 14, inclines outwardly at an obtuse angle with respect to this edge of the panel. This incline extends to the inner edge of the seam area 4 so as to extend completely across the gusset area 8. The outer end 28 of the lip 16 is inclined outwardly with respect to the upper transverse edge 14 of the panel 2 in the opposite direction to the end 26 of lip 12 but at the same angle to the upper edge 14 of panel 2 as the end 26 of lip 12. It should be noted furthermore that the inner ends of the inclined ends 26 and 28 of the lips 12 and 16 are curved or convexed slightly, as indicated

2

at 30, for a purpose to be brought out presently. It should be noted also that, by inclining the ends 26 and 28 of the lips 12 and 16 as just described, the ends of the outer halves 9 and 11 of the gusset areas at the upper end of the blank will be longer than the ends of the inner halves 13 and 15 of the gusset areas.

As already noted, the lower or bottom end of the bag blank is complementary to the upper end, so that a multiplicity of blanks may be formed from a continuous web without waste of material. As a result of this complementary feature, a projecting lip 32 is provided at the lower end of the panel 2, the side edges 27 and 29 of this lip inclining outwardly in opposite directions at an obtuse angle with respect to the lower transverse edge of the lip. The inclined edge 27 of this lip extends across the lower end of gusset area 8 to the inner edge of the seam area 4, while the inclined edge 29 of the lip extends across the gusset area 10 to the inner edge of panel 6. By inclining the edges 27 and 29, the outer half 9 of gusset area 8 at the lower end of this area is shorter than the inner half 13 of the gusset at the same end, and the outer half 11 of gusset area 10 at its lower end is shorter than the inner half 15 of this gusset at this end. It will be observed also that the material of the blank at the inner ends of the inclined edges 27 and 29 will be concaved, as shown at 31, because of the convex ends 30 of the edges 26 and 28.

In forming a bag from the blank of Fig. 1, the inner halves 13 and 15 of the gusset areas are infolded over upon panel 2 along the longitudinal fold lines 38 and 40, which extend along each side edge of this panel. The material is then outfolded along the longitudinal fold lines 42 and 44, to produce a gusset along the sides of panel 2. The material is then infolded along longitudinal fold lines 46 and 48. In making the fold along lines 46 and 48, the side seam area 4 and panel 6 will be infolded, to bring the outer edge portion of panel 6 into overlapping relation to the side seam area 4. When the area 4 and outer edge portion of panel 6 are pasted together, a full side seam is provided.

To bottom the bag the lip 32 at the lower end of the blank is folded over upon the outer face of panel 6 along the transverse fold line 52. This fold line 52, as will be observed from Fig. 1 in particular, is below the lower end 54 of seam area 4 and below the lower end 56 of rear panel 6 but is so positioned as to extend not only completely across the lower end of front panel 2 but completely across the inner halves 13 and 15 of the gusset areas 8 and 10 as well. This fold line, however, extends only partially across the outer halves 9 and 11 of the gusset areas 8 and 10, intersecting the inclined edges 27 and 29 of the lip 32 intermediate the fold lines 42 and 46 and intermediate the fold lines 44 and 48. Consequently, when the projecting lip 32 is folded over upon the panel 6 along the fold line 52, the lower ends 58 and 60 of the inner halves 13 and 15 of gusset areas 8 and 10 will be folded over so as to lie intermediate the inner face of the projecting lip 32 and the outer face of the panel 6. At the same time, the areas or corners 62 and 64 of the outer halves 9 and 11 of the gusset areas 8 and 10 will have been folded over upon the outer face of the outer halves of the gusset areas so as to become pinched between the folded-over portions 58 and 60 of the inner halves 13 and 15 of the gusset areas and the outer faces of the outer halves 9 and 11 of the gusset areas. It will be understood that in the bottoming operation the lip 32 is pasted to the outer face of panel 2, and, by convexing the inner ends of the inclined ends 26 and 28 of the lips 12 and 16 so that the inner ends of the edges 27 and 29 of the lip 32 are concaved, the full width of that portion of the lip composed of the end of panel 2 is available for pasting.

From the foregoing it will be seen that the construction

above described provides a gusseted, long-lip, square bag in which, in bottoming the bag, the projecting lip on the bottom end of the front wall of the bag is pasted directly to the outer face of the rear wall of the bag, the ends of the two gussets being infolded with the portions 62 and 64 of the outer half of each gusset area pinched between the inner half of each gusset area and the face of the outer half, so that displacement of the gusset ends at the corners of the bag bottom is prevented.

In the embodiment of the invention illustrated in Figs. 3 and 4, the bag blank provides a panel or wall 102, seam area 104, panel or wall 106, and gusset areas 108 and 110, the gusset area 108 being intermediate panel 102 and seam area 104, and gusset area 110 being intermediate panels 102 and 106.

As will be apparent from Fig. 3, the blank is so cut or shaped that a projecting lip 112 projects beyond the upper edge 114 of the panel 102 at one side edge of the panel, this lip embracing the upper ends of the seam area 104 and gusset area 108, while at the other side edge of the panel 102 a projecting lip 116 is provided, which projects beyond the upper edge 114 of the panel 102 and embraces the upper ends of panel 106 and gusset area 110.

The inner edge 126 of the lip 112 inclines outwardly at an obtuse angle with respect to the upper edge 114 of panel 102, the incline terminating at its outer end at the inner edge of seam area 104. The inner edge 128 of the lip 116 inclines outwardly at an obtuse angle with respect to the upper edge 114 of panel 102, this incline terminating at its outer end at the inner edge of panel 106. The slats of the lip edges 126 and 128 with respect to the upper edge 114 of panel 102 are alike.

As distinguished from the blank of Fig. 1, the inner ends of the inclined or slanting edges 126 and 128 are not convex but continue at an inclination to a short distance beyond the side edges of the panel 102.

As in the embodiment of the invention illustrated in Figs. 1 and 2, the lower end of the blank of Fig. 3 is complementary to the upper end. As a result, the lower end of panel 102 has a projecting lip 132, the side edges 127 and 129 of which incline outwardly at an obtuse angle with respect to the lower edge of the lip. The inclined edge 127 extends across the gusset area 108 and terminates at the inner edge of the seam area 104, while the inclined edge 129 extends across the gusset area 110 and terminates at the inner edge of panel 106.

In forming a bag from the blank of Fig. 3, the blank is infolded along the longitudinal fold lines 138 and 140 at each side of panel 102. The blank is then unfolded along longitudinal fold lines 142 and 144 and then infolded again along longitudinal fold lines 146 and 148. These folds will produce a longitudinal gusset along each side of the panel 102, and the seam area 104 and panel 106 will have been overlapped, so that, when pasted, a full side-seam is provided.

The bag is bottomed by folding the lip 132 at the lower end of the blank over upon the outer face of panel 106 along the transverse fold line 152. This fold line is below the lower end 154 of seam area 104 and the lower end 156 of rear panel 106 but is so positioned as to extend not only completely across the lower end of front panel 102 but the inner halves 113 and 115 of the gusset areas 108 and 110 as well. This fold line, however, extends only partially across the outer halves 109 and 111 of the gusset areas intersecting the inclined edges 127 and 129 of the lip 132 intermediate the fold lines 142 and 146 and intermediate the fold lines 144 and 148. Consequently, when lip 132 is folded over upon the panel 106, the lower ends 158 and 160 of the inner halves 113 and 115 of the gusset areas will be folded over so as to lie intermediate the inner face of the lip 132 and outer face of panel 106. At the same time, the areas or corners 162 and 164 of the outer halves 109 and 111 of the gusset areas will have been folded over upon the outer face of the outer halves of

the gusset areas, to become pinched between the folded-over portions 158 and 160 of the inner halves 113 and 115 of the gusset areas and the outer face of the outer halves 109 and 111 of the gusset areas. It will be understood that lip 132 is finally pasted to the outer face of panel 102. It will be appreciated that, because the two ends of the blank are complementary, the side edges 127 and 129 of the lip 132 terminate at their inner ends a short distance inside the fold lines 138 and 140 or the sides of the panel 102, so that a pasting area is provided at the end of the lip 132 extending from fold line 138 to fold line 140.

It will be apparent that in both embodiments illustrated and described a construction is provided whereby a gusseted bag is produced in which displacement of the gussets at the two corners of the bag bottom with consequent leakage of the bag contents is prevented.

It is to be understood that changes may be made in the constructions disclosed, within the purview of the invention.

What we claim is:

1. A bag blank comprising a panel area; a side seam area and a gusset area integral with each other and with said panel area, the said side seam and gusset areas extending along one side of the said panel area, with the gusset area intermediate the side seam and panel areas; and a second panel area and an integral gusset area extending along the opposite side of the first-mentioned panel and integral therewith, with the second gusset area intermediate the two panels; the said side seam area and first-mentioned gusset area projecting beyond one end of said first-mentioned panel area to provide a projecting lip, the end of said lip inclining outwardly from the end of the first-mentioned panel area toward the outer side edge of the blank to the inner edge of the side seam area; said second-mentioned gusset area and second-mentioned panel area projecting beyond the said end of said first-mentioned panel area to provide a projecting lip, the end of said second lip inclining outwardly from the end of the first-mentioned panel area toward the outer side edge of the second-mentioned panel to the inner edge of the second-mentioned panel area, the end of said blank opposite said lipped end being complementary to the said lipped end.

2. A bag blank comprising a panel area; a side seam area and a gusset area integral with each other and with said panel area, the said side seam and gusset areas extending along one side of the said panel area, with the gusset area intermediate the side seam and panel areas; and a second panel area and an integral gusset area extending along the opposite side of the first-mentioned panel and integral therewith, with the second gusset area intermediate the two panels; the said side seam area and first-mentioned gusset area projecting beyond one end of said first-mentioned panel area to provide a projecting lip, the end of said lip inclining outwardly from the end of the first-mentioned panel area toward the outer side edge of the blank to the inner edge of the side seam area; said second-mentioned gusset area and second-mentioned panel area projecting beyond the said end of said first-mentioned panel area to provide a projecting lip, the end of said second lip inclining outwardly from the end of the first-mentioned panel area toward the outer side edge of the second-mentioned panel area to the inner edge of the second-mentioned panel area, the ends of the lips adjacent the side edges of the first-mentioned panel area being convex, the end of said blank opposite said lipped end being complementary to the said lipped end.

3. A bag blank comprising a panel area of rectangular configuration; a side seam area and a gusset area integral with each other and with said panel area, the said side seam and gusset areas extending along one side of the panel area, with the gusset area intermediate the side

seam area and panel; and a second panel area and an integral gusset area extending along the opposite side of the first-mentioned panel and integral therewith, with the last-mentioned gusset area intermediate the two panels, the said side seam area and first-mentioned gusset area projecting beyond one end of said first-mentioned panel area to provide a projecting lip the inner edge of which inclines outwardly at the end of the first-mentioned panel area from a point slightly inside the side edge of the panel toward the outer side edge of the blank and terminates at the inner edge of the side seam area, the end of the side seam area extending at right angles to the side of this area, said second-mentioned gusset area and second-mentioned panel area projecting beyond the said end of said first-mentioned panel area to provide a projecting lip the inner edge of which inclines outwardly at the end of the first-mentioned panel area from a point slightly inside the side edge of the panel toward the adjacent outer side edge of the blank and terminates at the inner edge of the second-mentioned panel area, the end of the second-mentioned panel extending at right angles to the side of this area, the end of the blank opposite said lipped end being complementary to the said lipped end.

4. A bag composed of a single piece of material, said bag comprising a front wall and a rear wall; a gusset extending along each side of the bag intermediate the two bag walls; and a foldable closure lip at the bottom end

5 of the bag, said lip extending across the entire bottom end of the front bag wall and then sloping so that the bottom end of the inner half of each gusset immediately adjacent the side edges of the front wall projects beyond the bottom end of the other or outer half of each gusset, said lip being folded over upon the outer face of the rear wall of the bag along a transverse fold line extending across the lip from one edge to the other, said fold line lying below the inner end of the lip and traversing the longer or inner half of each gusset for its entire width but traversing the shorter or outer half of each gusset for only part of the width of this half of the gusset, that portion of the outer half of each gusset which is traversed by said transverse fold line being pinched between the inner half of the gusset and the untraversed portion of the outer half of the gusset.
